Primary Examiner—T. Tung

CLAIM

The ornamental design for a fetus pulse and blood flow detector, as shown and described.

DESCRIPTION

FIG. 1 is the front end view showing the fetus pulse and blood flow detector,
FIG. 2 is the rear end view thereof,
FIG. 3 is the side view thereof,
FIG. 4 is the top plan view thereof; and
FIG. 5 is a perspective front view thereof showing in dotted lines, for illustration only, the attachment of the device to a stethoscope.

FIG. 4**FIG. 1****FIG. 3****FIG. 2****FIG. 5**
